UNITED STATES PATENT OFFICE.

HARRY WEARNE, OF RIXHEIM, GERMANY.

DESIGN FOR WALL-PAPER.

SPECIFICATION forming part of Design No. 29,658, dated November 8, 1898.

Application filed October 13, 1898. Serial No. 693,460. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, which represents a plan view of a portion of a strip of wall-paper embodying the features of my design.

The design consists of a bar-figure A, at the bottom of which a foliate figure α appears, and at the top of the bar a scroll B is produced, having foliate side extensions b and similar pendants b' , and a floral arch C is located between the scroll extensions b . Floral sprays D connect with the extremities of the scroll-pendants b' and with the end portions of the bar, and below the foliate figure α a bouquet E of flowers is drawn, having a bell center e and a foliate bell-pendant e' . 20

I claim—

The design for wall-paper herein shown and described.

HARRY WEARNE.
